(57) **CLAIM**

The ornamental design for a universal exercise bar and pull-up apparatus, as shown and described.

DESCRIPTION

FIG. 1 is a perspective view of a universal exercise bar and pull-up apparatus showing my new design.

FIG. 2 is a top plan view thereof.

FIG. 3 is a bottom plan view thereof.

FIG. 4 is a right side elevational view thereof, the opposite side being a mirror image thereof.

FIG. 5 is a rear elevational view thereof; and,

FIG. 6 is a front elevational view thereof.
